UNITED STATES PATENT OFFICE.

JACOB HERBRAND, OF FREMONT, OHIO, ASSIGNOR TO THE HERBRAND COMPANY, OF SAME PLACE.

DROP-PERCH FOR VEHICLES.

SPECIFICATION forming part of Letters Patent No. 276,967, dated May 1, 1883.

Application filed October 6, 1882. (No model.)

To all whom it may concern:

Be it known that I, JACOB HERBRAND, of Fremont, in the county of Sandusky and State of Ohio, have invented certain new and useful Improvements in Drop-Reach Gears for Vehicles, of which the following is a specification, reference being had to the accompanying drawings.

My invention consists in certain improvements upon the carriage-gear for which Letters Patent of the United States No. 244,599 were granted to me July 19, 1881, and are specifically designated in the appended claims.

In the accompanying drawings, illustrating my invention, Figure 1 is a plan view with portions broken away. Fig. 2 is a side elevation, partly in section, the front axle being partly turned, as in Fig. 1. Fig. 3 is a vertical section on the line 3 3 of Fig. 1, and Fig. 4 is a similar section on the line 4 4 of Fig. 1.

The object of one part of my improvements is to strengthen, in a convenient and economical manner, the security of the end attachments of the wooden reach to the metallic parts which are connected to the axles, and to provide a simple and convenient way of securing the lower fifth-wheel plate to the axle.

Referring to the letters upon the drawings, A indicates the wooden or main part of the reach; B, the rearward extension or reach-bar of the upper plate of the fifth-wheel, and C the metallic back coupling connecting the rear end of the reach with the rear axle. Upon the extension B and upon the back coupling, C, I provide two downwardly-projecting lugs, D D, to bear against the opposite sides of the reach near its ends. Bolts d pass through the bar B and reach, and through the back coupling and reach, respectively, between the respective pairs of lugs D D. These lugs form stays or clamps upon each side of the wooden reach where the end bolts pass through it, and serve to hold the reach ends firmly and to prevent them from splitting where weakened by the bolt-holes. These lugs also serve to render the bar B and coupling C as strong at the parts

where the holes for the bolts d d are made as elsewhere.

I am aware that sockets have heretofore been provided for reach ends; but these are comparatively expensive and cumbersome; hence I have devised a lighter, cheaper, and simpler form of reach-end fastening, by which the weight of the gear, as well as its first cost, is reduced and its strength still adequately maintained.

In order to provide against the tilting of one of the fifth-wheel plates with reference to the other when the carriage is being turned, and when the axle is cramped or brought to an acute angle with reference to the reach, I provide projections or coincident bearing-lugs E upon the upper and lower plates of the fifth-wheel, so that there shall be the same bearing and length of leverage to keep the plates parallel to each other under tilting or twisting strain, when the axle is cramped, as when it stands at right angles to the reach. These lugs are light, and can be cheaply formed by casting upon the upper and lower plates, F and G, of the fifth-wheel.

H indicates longitudinal extensions or clip-bearings of the lower fifth-wheel plate, adapted to receive axle-clips or straps h h to bind the plate to the front axle. These straps are found practically superior to bolts, or to clips which pass through the fifth-wheel plates or parts thereof, or to any other means of fastening heretofore employed of which I am aware, because bolts weaken the axle and plates, and clips passing through the plates necessarily weaken them.

Having thus described my invention, what I claim, and desire to secure by Letters Patent of the United States, is—

1. The combination of the reach, the reach-bar B, having the pair of lugs D D, and the bolt d, passing through the reach and reach-bar between the lugs, as and for the purpose set forth.

2. The combination of the fifth-wheel plate F, the reach-bar B, having the lugs D D, the reach A, the bolt passing through the reach-

bar and reach between said lugs, the back coupling, its lugs, and the bolt passing through the reach and back coupling between its lugs, as and for the purpose set forth.

5 3. The combination of the front axle, the lower fifth-wheel plate, G, its end extensions or clip-bearings, H, and the clips, h, embracing said bearings and the axle, all as and for the purpose set forth.

In testimony whereof I have hereunto subscribed my name this 22d day of September, A. D. 1882.

JACOB HERBRAND.

Witnesses:

MARCUS S. HOPKINS,
NELLIE HOLMES.
